UNITED STATES PATENT OFFICE.

WALTER J. RUDOLPH, OF CHICAGO, ILLINOIS. ASSIGNOR TO THE IMPERIAL BRASS MANUFACTURING COMPANY, OF CHICAGO, ILLINOIS, A CORPORATION OF ILLINOIS.

ADJUSTING DEVICE.

Application filed December 1, 1922. Serial No. 604,266.

To all whom it may concern:

Be it known that I, WALTER J. RUDOLPH, a citizen of the United States, and a resident of Chicago, in the county of Cook and State 5 of Illinois, have invented certain new and useful Improvements in Adjusting Devices, of which the following is a specification.

My invention is concerned with adjusting devices, and is designed primarily to produce such a device as can be quickly installed 10 on either the instrument board (if one is employed) or on the dashboard of a Ford automobile and used to control the mixture by determining the exact adjustment of the carburetor-gas needle.

To illustrate my invention, I annex hereto a sheet of drawings, in which the same reference characters are used to designate identical parts in all the figures, of which,—

20 Fig. 1 is a perspective view with some of the parts broken away, showing my invention as applied to the instrument board;

Fig. 2 is a plan view of the dial member;

25 Fig. 3 is a view of the same as seen from the under side of Fig. 2;

Fig. 4 is a detail in central vertical section through the gear-supporting bracket and gears; and

30 Fig. 5 is a perspective view of a part thereof showing the dial adjusted on the dashboard.

Referring to Fig. 1, 10 is the instrument board, if one is employed, 11 is the dashboard having the customary slot 12 therethrough, and 13 is the carburetor of the engine for the Ford automobile. The carburetor-gas needle 14 is threaded in the top 35 of the carburetor and is provided with the cross head 15 having the apertures 16 therein.

40 Prior to my invention, the carburetor adjustment has been controlled by the rod 17 having a fork 18 on its lower end extending through the holes 16, and, with the rod extending up through the slot 12 and terminating 45 in a ring by which it was manipulated. So much of the apparatus is old, and, per se, forms no part of my invention.

50 In order to readily make a more perfect adjustment of the position of the needle 14, I provide the dial member 20, which preferably consists of a sheet-metal plate having the body portion thereof substantially semi-circular and with the graduation 21 thereon. I preferably mark the central graduation 0,

and to the left I use the odd numbers 1, 3, 55 5 and 7, and to the right I use the even numbers 2, 4, 6 and 8. The connections are adjusted so that when the pointer 22 stands opposite 0, the needle 14 is set for the average mixture at which the engine will ordinarily run, and when it is turned to the left, the needle is unscrewed and a richer mixture furnished, so that it is preferably marked "Rich" below the 7 and "Lean" below the 8. The body 20 of the dial is provided with a pair of apertures for the screw bolts 23, and also has the flange 24 turned at right angles to the body, and provided with apertures 25 to be employed as herein-after described.

50 Co-operating with the dial member is the supporting plate, preferably made of a sheet-metal stamping, and consisting of the rectangular body portion 26 having a pair of apertures therein for the screws 27, and with the flange 28 extending obliquely therefrom, and provided with a pair of apertures for the short screw bolts 29 seen in Fig. 5. The body 26 is preferably provided on the side opposite to the flange 28 with a short flange 30 extending at right angles to said body. Where the instrument board 10 is employed, the dial is adjusted by placing the parts in the position shown in Fig. 1, and passing the screw bolts 23

80 through the apertures in the body portions of the dial 20 and the supporting plate 26, and clamping the edge of the instrument board 10 between said members by the action of the nuts on the screws, which pass below the bottom of the instrument board, and thus obviate the necessity of doing any boring in said board to locate the dial plate in position. The pointer 22 has the hub or socket portion 31 in which is secured the end of the shaft 32 which is journaled in opposed apertures, not seen, in the body portions of the dial 20 and the supporting plate 26. Said rod 32 extends through the slot 12, and is secured by the set screw 33 in the hub 34 of the bevel gear-wheel 35 meshing with the bevel gear wheel 36 having the hub 37 in which is secured the upper end of the above-mentioned rod 17 by the set screw 38. It will be understood of course that the rod 17 has had the ring 19 cut off and shortened up to the proper length so that it will extend downward from

the hub 37 and have its fork 18 co-operate with the apertures 16 in the cross head 15 in the customary manner.

To support the gear wheels 35 and 36, I 5 employ the bracket shown, which consists of a sheet-metal stamping having the two body portions 39 and 40, which diverge from each other at the proper angle to give the wheels 35 and 36 the desired angular relation. 10 These wheels preferably consist of circular sheet-metal stampings with the teeth cut on the edges and turned up slightly as shown, and said wheels are secured on the shoulders 41 of their respective hubs by 15 swaging over the ends of said reduced portions forming the shoulders. Below these shoulders 41 are other shoulders 42, the reduced portion between the shoulders 41 and 42 furnishing the bearing surface for the 20 hubs which are journaled in apertures 43 formed in the bodies 39 and 40 for this purpose. The bodies 39 and 40 are connected by the web portion 44, which is preferably trough-shaped in section, and at the top of 25 the bracket I place the flange 45, which has a pair of apertures therein for the screws 46 by which the bracket is secured in place on the rear of the dashboard 11. The flange 45 is connected with the body portion 39 30 by the web 47, which is of suitable shape to support the body portions 39 and 40 in the desired relation to the rear of the dashboard 11.

Where the instrument board 10 is not employed, as illustrated in Fig. 5, the gear-supporting bracket is mounted as before, but the shaft 32^a is shortened substantially and the supporting plate 26 is secured to the front of the dashboard 11, as shown in Fig. 40 5, by the screws 27, and the dial is secured thereto by having its flange 24 overlap the flange 28 and securing the two flanges together by the short screw bolts 29.

While I have shown and described my invention as embodied in the form which I at 45 present consider best adapted to carry out its purposes, it will be understood that it is capable of modifications, and that I do not desire to be limited in the interpretation 50 of the following claims except as may be necessitated by the state of the prior art.

What I claim as new, and desire to secure by Letters Patent of the United States, is:

1. In a device of the class described, the 55 combination with a dial and clamping means for securing it in place on an instrument board, of a gear bracket and means for securing it in place, a pair of meshing bevel gear wheels journaled in the bracket, 60 a pointer co-operating with the dial, a rod having the pointer secured on one end and one of the gear wheels on the other journaled in the dial, and a second rod secured at one end in the other gear wheel and terminating in universal-joint connections.

2. In a device of the class described, the combination with a dial and supporting means adapted to be secured in place on either the bottom of the instrument board or the face of the dashboard of an automobile, 70 of a gear bracket and means for securing it in place, a pair of meshing bevel gear wheels journaled in the bracket, a pointer co-operating with the dial, a rod having the pointer secured on one end and one of the 75 gear wheels on the other journaled in the dial, and a second rod secured at one end in the other gear wheel and terminating in universal-joint connections.

3. In a device of the class described, the combination with a dial, of a co-operating supporting plate, the plate and dial being so designed that by securing them together in different positions they can be secured on either the bottom of the instrument board or 80 on the face of the dashboard of an automobile, a gear bracket, means for securing it in place on the engine side of the dashboard of an automobile, a pair of meshing bevel gear wheels journaled in the bracket, 90 a pointer co-operating with the dial, a rod having the pointer secured on one end and one of the gear wheels on the other journaled in the dial, and a second rod secured at one end in the other gear wheel and terminating in universal-joint connections.

4. In a device of the class described, the combination with a dial member having a flange turned at substantially a right angle to the body thereof and with bolt apertures 100 in the body and in the flange, of a co-operating supporting plate having a flange at an obtuse angle to the body thereof with bolt apertures in the body and in the flange, and bolts to connect said members, they being 105 designed so that the bodies of the dial members and the supporting plate may be secured on opposite sides of the edge of a support by bolts passing through the apertures in the bodies, or the body of the supporting plate may be secured to the support and the dial member secured thereto by bolts passed through the apertures in the flanges.

5. In a device of the class described, the combination with a dial member having a flange turned at substantially a right angle to the body thereof and with bolt apertures 115 in the body and in the flange, of a co-operating supporting plate having a flange at an obtuse angle to the body thereof with bolt apertures in the body and flange, and a second narrow flange at right angles to the body and on the opposite side from the other flange, and bolts to connect said members. 120 they being designed so that the bodies of the dial member and the supporting plate may be secured on opposite sides of the edge of a support by bolts passing through the apertures in the bodies with the edge of the dial-member flange resting on the narrow 125 flange.

supporting-plate flange, or the body of the supporting plate may be secured to the support and the dial member secured thereto by bolts passing through the apertures in the flanges.

6. In a device of the class described, the combination with a curved dial plate graduated through substantially a semicircle, a rod journaled at the center of the dial 10 graduations, and a pointer on the rod cooperating with the graduations, said graduations being marked with increasing odd numbers from the center marked 0 on one

side and with increasing even numbers from the center on the other side. 15

7. In a device of the class described, a gear wheel consisting of a cylindrical hub portion with two successively reduced end portions and a bevel wheel stamped from sheet metal and swaged on the outermost 20 reduced end of the hub portion.

In witness whereof, I have hereunto set my hand this 29th day of November, 1922.

WALTER J. RUDOLPH.

In the presence of a witness—

JOHN HOWARD McELROY.
